UNITED STATES PATENT OFFICE

139,249

DESIGN FOR A PRE-FLIGHT AIRCRAFT PILOT TRAINER

Volmer S. Jensen, Glendale, Calif., assignor to
California Aero Glider Co., Inc., a corporation
of California

Application July 5, 1943, Serial No. 110,609

Term of patent 14 years

(Cl. D71—1)

To all whom it may concern:

Be it known that I, Volmer S. Jensen, a citizen
of the United States and a resident of Glendale,
in the county of Los Angeles, State of California,
have invented a new, original, and ornamental
Design for Pre-flight Aircraft Pilot Trainer, of
which the following is a specification, reference
being had to the accompanying drawings, forming
part thereof.

In the drawings:

Fig. 1 is a top plan view of a pre-flight aircraft
pilot trainer showing my new design;

Fig. 2 is a side perspective view of the same;

Fig. 3 is a front end perspective view; and

Fig. 4 is a rear end perspective view.

I claim:

The ornamental design for a pre-flight air-
craft pilot trainer, as shown.

VOLMER S. JENSEN.
